United States Patent Office.

ERNEST QUAST, OF FREEDOM, MISSOURI.

Letters Patent No. 96,837, dated November 16, 1869.

IMPROVEMENT IN AXES.

The Schedule referred to in these Letters Patent and making part of the same.

To all whom it may concern:

Be it known that I, ERNEST QUAST, of Freedom, in the county of La Fayette, and State of Missouri, have invented a new and useful Improvement in Axes; and I do hereby declare that the following is a full, clear, and exact description thereof, which will enable others skilled in the art to make and use the same, reference being had to the accompanying drawing, forming part of this specification.

This invention relates to improvements in wood-chopping axes, whereby it is designed to provide an improved construction of axes, with removable bits, for the substitution of others, when worn too thick and blunt for use.

The invention consists in making the polls in two parts, divided in the plane of the cutting-edge, and shaped so that when put together and joined by rivets, a groove will be formed, dovetailed at the base, for holding the bits, which are fitted to it, so that a part of the rivets will pass through the tongues fitted to the said grooves.

Figure 1 represents a side view of an axe, made according to my improvement.

Figure 2 represents a section of the same, taken on the line $x-x$ of fig. 1.

Similar letters of reference indicate corresponding parts.

I propose to make the polls in two parts, A, divided on the line B, and to secure them with rivets or screws C.

For connecting the steel bits D to these polls, I

shape them so that when the two parts are put together, a groove, E, will be formed, for the reception of a tongue, F, of the bit.

These grooves I prefer to make dovetailed at the base, by raising the ribs G, in the rebates formed in each half of the polls, and I form corresponding grooves in the tongues F of the bits.

I prefer to under-cut the shoulders H of the bits, at the base of the tongues, and fit the lips of the polls thereto; as shown in fig. 2.

I prefer to use four rivets for securing the two parts of the polls, two of them passing through the tongues of the bits.

The polls may be made of cast-iron, malleableized or not, or they may be of fibrous metal, rolled into bars, and cut into the proper lengths.

When so constructed, the bits may be readily removed by removing the two rivets, which pass through the bits, and sliding the bits through the grooves.

Having thus described my invention,

What I claim as new, and desire to secure by Letters Patent, is—

Axe-polls, constructed in two parts A, shaped and secured as described, and the bits, joined thereto by a tongued and grooved connection, all substantially as specified.

ERNEST QUAST.
